BUCKLE FOR STIRRUP STRAPS

Lester H. Hamley, Pendleton, Oreg.

Application March 14, 1944, Serial No. 526,440

1 Claim. (Cl. 24—176)

1

This invention relates generally to the saddles art and particularly to a buckle for stirrup straps.

The main object of this invention is to provide an exceedingly simple and efficient form of buckle for adjusting the length of a stirrup strap.

The second object is to construct a buckle of the class described whereby a stirrup strap may be easily adjusted in a fraction of the time ordinarily required for this purpose.

The third object is to produce a buckle of the class described which has but one part and which will not become inoperative for any ordinary reason.

A further object is to construct a buckle of the class described which will not be bulky or cumbersome and whose holding action will be increased as the strains thereon increase.

I accomplish these and other objects in a manner set forth in the following specification as illustrated in the accompanying drawing, in which:

Fig. 1 is a side elevation of a stirrup strap viewed from the side nearer the horse.

Fig. 2 is a plan of the buckle at an enlarged scale.

Fig. 3 is a side elevation of the buckle.

Fig. 4 is a rear elevation of the buckle.

Fig. 5 is a section taken along the line 5—5 in Fig. 4 and showing fragments of the related leather portions of the stirrup strap.

Similar numbers refer to similar parts throughout the several views.

Referring in detail to the drawing, there is shown a common form of fender 10, whose upper end 11 passes through the supporting ring 12 of saddle 13, which is merely indicated as it forms no part of the present invention. The end 11, which passes through the ring 12, turns downwardly to form the stirrup strap 14 which is provided with dual perforations 15.

The lower end 16 of the fender 10 terminates in the two fastening straps 17 and 18, to which is secured the loop 19. The usual stirrup 20 is attached by means of the bolt 21. The portions thus far referred to are those in common use.

Referring more particularly to my invention, same will be seen to consist of a buckle B composed of a back plate 22 and a front plate 23, which is stepped with relation to said back plate and spaced from and inclined slightly with relation to the back plate 22 and held in fixed relation thereto by the side members 24. The front plate 23 has projecting therefrom the two hooks 25 which extend in the direction of the back plate 22 and slightly beyond the outermost face of the back plate 22. The back plate 22 is provided with two perforations 26 to receive the

2

rivets 27, by means of which the buckle is attached to the fastening straps 17 and 18.

In the use of this device it is only necessary to pass the strap end 28 between the plates 22 and 23, permitting the hooks 25 to enter the set of holes 15 which will provide the desired stirrup length. It can be seen that the greater the strain placed on the stirrup 20 the more firmly will the hooks 25 engage the holes 15. There is no possibility of the parts becoming disengaged unless they are purposely manipulated in a manner that the strap 14 may be freed from the hooks 25, which it is necessary to do before the stirrup length can be changed.

15 In other words, the strap end 28 must be placed perpendicular to the plane of the buckle between the members 22 and 23 in order that the strap may pass between same. Then when the prongs 25 are in contact with the proper pair of openings 15 in the strap to give the proper adjustment, the buckle is tilted to a position in the same plane as the strap 14.

While I have thus illustrated and described my invention, it is not my intention to be limited 25 to the precise form shown herein, and I intend to cover such forms and modifications of the invention as fall fairly within the appended claim.

I claim:

30 A buckle for stirrup straps, consisting of a flat back plate perforated to permit straps to be secured to opposite faces thereof, and terminating along one edge of the plate, a front plate offset from said back plate and inclined with relation thereto, said front plate having one edge adjacent to said back plate and spaced therefrom, and having the opposite edge sloping toward the plane of the back plate, the sloping edge having a curved form, the rear side of which is provided with hooks curved toward the back plate, and extending beyond the plane of the back plate, and a pair of flat side plates integral with said front and back plates and pointed toward the opposite ends of the buckle.

LESTER H. HAMLEY.
